(57) **CLAIM**

I claim the ornamental design for a plumbing fixture accessory plate, as shown and described.

DESCRIPTION

FIG. 1 is a perspective view of a plumbing fixture accessory plate according to the invention;

FIG. 2 is another perspective view of the plumbing fixture accessory plate of FIG. 1;

FIG. 3 is a top plan view of the plumbing fixture accessory plate of FIG. 1, which is identical to the bottom plan view;

FIG. 4 is a front elevation view of the plumbing fixture accessory plate of FIG. 1;

FIG. 5 is a back elevation view of the plumbing fixture accessory plate of FIG. 1;

FIG. 6 is a right side view of the plumbing fixture accessory plate of FIG. 1; and,

FIG. 7 is a left side view of the plumbing fixture accessory plate of FIG. 1.

1 Claim, 7 Drawing Sheets
